UNITED STATES PATENT OFFICE.

HOWARD I. MORRIS, OF SAN DIEGO, CALIFORNIA, ASSIGNOR TO THE SAVAGE TIRE COMPANY, OF SAN DIEGO, CALIFORNIA, A CORPORATION OF CALIFORNIA.

LOOM ELEMENT.

1,276,945.

Specification of Letters Patent. Patented Aug. 27, 1918.

Original application filed September 9, 1916, Serial No. 119,208. Divided and this application filed December 1, 1916. Serial No. 134,480.

To all whom it may concern:

Be it known that I, HOWARD I. MORRIS, a citizen of the United States, residing at San Diego, in the county of San Diego and State of California, have invented new and useful Improvements in Loom Elements, of which the following is a specification.

This invention relates to loom elements, and more particularly to the shed-forming means of looms, or the means whereby the warp threads or thread elements or groups of warp threads or thread elements are relatively separated in alternately opposite relations, to produce the shed formations which permit the introduction of the weft threads or thread elements or groups of weft threads or thread elements. The present invention comprises one of the associated or combined or inter-related features or elements disclosed in a prior application for U. S. Letters Patent, for looms, filed by me September 9, 1916, Serial No. 119,208.

The invention has for its objects the provision of improved loom elements or an improved loom element, pertaining to shed-forming means, which will be superior in point of relative simplicity and inexpensiveness in construction and formation, taken in connection with durability, positiveness and reliability in operation, and compactness in form, which will be generally superior in efficiency and serviceability.

With the above and other objects in view, the invention consists in the novel provision, formation and construction of parts and features, which parts and features taken together constitute an improved shed-forming means, element or finger, all as herein-after described, shown in the drawing and finally pointed out in claims.

In the drawing:

Figure 1 is a front elevation of an improved shed-forming finger constructed to constitute shed-forming means embodying the invention;

Fig. 2 is a side elevation thereof;

Fig. 3 is a top plan view thereof;

Fig. 4 is a view similar to Fig. 1 showing a pair of the shed-forming fingers in relative positions to produce the shed, comprising a pair of the warp thread elements; and

Fig. 5 is an isometric view showing a plurality of pairs of the shed-forming fingers

arranged relatively to produce the shed including a plurality of warp thread elements. 55

In Figs. 2, 3, 4 and 5 warp thread elements are shown as associated with the shed-forming finger or fingers, to illustrate the principle of action and mode of operation or method of use of the invention, and to disclose the working relation between the shed-forming finger or fingers and the warp thread elements.

Corresponding parts and features in all the figures are designated by the same reference characters.

Referring with particularity to the drawing, *a* designates warp thread elements, and *A* designates in each instance a thread-forming finger formed and constructed to embody the invention, and each having an elongated body portion *6* carrying an outwardly-facing rectangularly related terminal portion *6^a*, each of which latter is provided with a straight side edge *6^c* which is the leading 75 edge with relation to the direction of movement or progression of the finger if such finger or plurality thereof is mounted to move in or with relation to the path of supply or feed and final disposition of the warp 80 thread elements; the nature of such mounting or the means of so moving the fingers being immaterial in so far as the present invention is concerned. Each such outwardly-facing rectangularly related terminal portion *6^a* is likewise provided with an upwardly inclined and rounded edge portion *6^b* arranged oppositely to the straight edge portion *6^c*, and which merges into such straight edge portion in a point *6^d* which 90 constitutes specifically the end of the terminal portion *6^a*. The finger is likewise provided in the edge portion of the terminal portion *6^a* which is opposite to the straight edge portion *6^c*, and beneath the upwardly 95 curved edge portion *6^b*, with a suitable warp-thread receiving notch *6^e*, such notch being thus formed in the following edge of the finger terminal portion *6^a*. The terminal portion *6^a* is disposed slightly forwardly of the vertical plane of the flat straight body 100 *6*, being connected therewith by a neck *6^f* preferably rectangularly directed from said body portion *6*; and the terminal portion *6^a* is preferably flat in formation and lies in a 105 facial plane at right angles to the facial

plane of the body portion 6. The terminal portion 6^a, as shown, rises slightly above the top of the body portion 6 and its neck 6^f, and said terminal portion is directed laterally 5 from the neck 6^f entirely at one side thereof, so that the straight edge 6^e is flush with one face of the neck 6^f.

The operation, method of use and advantages, of the improved shed-forming means 10 or finger for looms constituting the invention, will be readily understood from the foregoing description, taken in connection with the accompanying drawing and the following statement:

15 The shed-forming finger or a plurality of the same may be supported and mounted in any preferred and suitable manner, and may be actuated in any suitable manner, so as to be properly applied to the warp thread elements *a*, to cause the relative separation of the same to produce the shed, or to produce a plurality of shed portions when, as usual, a plurality of such fingers are used, as illustrated in Fig. 5. The fingers are reciprocated lengthwise, each finger being so reciprocated in a direction the opposite of that taken at any given phase of reciprocation by the next adjacent finger, in producing a common form of shed. Or, certain 20 fingers may be grouped for joint reciprocation or reciprocation in a common simultaneous direction, or otherwise controlled and actuated, all within the predetermination and choice of the designer of the loom, and 25 all in accordance with the pattern or weave 30 of fabric to be produced by association of the weft thread elements with the warp thread elements. It is of course understood that the weft thread elements are applied 35 to the warp thread elements, or associated therewith, by a suitable shuttle element 40 which operates through the shed formation or formations in any desired or suitable manner. As each finger is actuated toward 45 and to the warp threads or thread units, as the latter are supplied in any suitable manner, the point 6^a is projected between two adjacent threads or thread elements, or two 50 series of threads or thread elements, producing a separation of such threads or thread elements or groups or series thereof, whereby it results that the thread or thread elements or group or series thereof which is 55 traversed or engaged or diverted by the rounded edge portion 6^b ultimately come into registration with the warp-thread receiving notch 6^e, and the tension upon such thread or threads or thread or thread elements causes the same to enter such notch 6^e. Thereupon, in a continuation of the 60 same movement or actuation of the finger, the thread or threads or thread or thread elements is or are diverted from the normal plane of the warp threads, and one-half of 65 a shed-formation is produced. As the di-

rection of actuation of movement of the finger is reversed, this half of the shed formation is caused to collapse and finally is succeeded by the production of the opposite one-half of a shed-formation. Where two 70 such fingers are jointly operated in opposite directions of actuation, it will be seen that complete shed formations will be produced as long as the threads or thread elements are in the respective notches 6^e, and the weft 75 threads are shot through such complete shed formation and thus associated with the warp thread elements.

Any suitable means may be provided, such as that disclosed in the application initially 80 hereinabove identified, for disengaging the warp threads or elements from the fingers and the notches 6^e therein, after the proper number of courses of weft thread elements have been associated with the warp thread 85 elements with which the fingers have been engaged in single or successive shed-producing action. Thereupon, the shed-forming fingers may be successively associated with and disengaged from other and further 90 warp thread elements for the production of further shed formations inclusive of such further warp thread elements. The terminal portion 6^a being offset from the common 95 plane of the body portion 6 and the neck 6^f, it results that the warp threads or elements *a* are conveniently accommodated, in the notch 6^e, at one side or adjacent to one face of the body portion 6 or the upper end thereof, or at one side of the neck 6^f. 100

It is manifest that the shed-forming finger constituting the invention is extremely simple in formation and may be inexpensively formed or produced from a single blank of suitable stock, and is of exceeding 105 inherent strength and durability and well qualified for positive and efficient performance.

It is manifest that changes and variations 110 and substitutions may be made with respect to the particular construction, formation and organization hereinabove described and shown in the drawing, without departing from the spirit of the invention or a fair interpretation thereof.

Having thus disclosed my invention, I 115 claim and desire to secure by Letters Patent:

1. A device of the character disclosed, comprising a body portion provided with a tapering working end portion angularly related to the body portion and having a thread-receiving notch in said end portion. 120

2. A device of the character disclosed comprising a body portion provided with a tapering working end portion angularly related to the body portion and having a thread-receiving notch in said end portion; said terminal portion being disposed forwardly of the body portion. 125 130

3. A device of the character disclosed, comprising a body portion provided with a tapering working end portion angularly related to the body portion and having a 5 thread-receiving notch in said end portion; said terminal portion being disposed forwardly of the body portion and directed laterally of the plane thereof.

4. A device of the character disclosed, 10 comprising a body portion provided with a tapering working end portion angularly related to the body portion and having a thread-receiving notch in said end portion; said terminal portion being disposed forwardly 15 of the body portion and directed laterally of the plane thereof whereby said notch is disposed at one side of the plane of the body portion.

5. A device of the character disclosed, 20 comprising a body portion provided with a tapering working end portion angularly related to the body portion and having a thread-receiving notch in said end portion; said terminal portion being disposed forwardly 25 of the body portion and directed laterally of the plane thereof whereby said notch is disposed at one side of the plane of the body portion; said body portion being provided with an angularly directed neck portion connecting the terminal portion of the body portion.

6. A device of the character disclosed, comprising a body portion provided with a tapering working end portion angularly related to the body portion and having a 35 thread-receiving notch in said end portion; said terminal portion having a straight edge and an oppositely disposed upwardly-inclined rounded edge.

40 7. A device of the character disclosed, comprising a body portion provided with a tapering working end portion angularly related to the body portion and having a thread-receiving notch in said end portion; said terminal portion having a straight edge, and an oppositely disposed upwardly-inclined rounded edge through which the notch is produced.

8. A device of the character disclosed, 50 comprising a body portion provided with a tapering working end portion angularly related to the body portion and having a thread-receiving notch in said end portion; said terminal portion being disposed forwardly 55 of the body portion and directed laterally of the plane thereof whereby said notch is disposed at one side of the plane of the body portion; said body portion being provided with an angularly directed neck portion connecting the terminal portion with the body portion.

60

the body portion; the terminal portion having a rounded edge through which the notch is produced.

9. A shed-forming finger for looms and the like, comprising an elongated flat body 65 portion terminating at its upper end in an angularly and forwardly directed neck, and a terminal portion carried by said neck and disposed forwardly of the body portion and directed laterally in one direction from the 70 neck and in a plane at right angles to the common plane of the body portion and the neck; said terminal portion being provided with a thread-receiving notch.

10. A shed-forming finger for looms and the like, comprising an elongated flat body portion terminating at its upper end in an angularly and forwardly directed neck, and a terminal portion carried by said neck and disposed forwardly of the body portion and 75 directed laterally in one direction from the neck and in a plane at right angles to the common plane of the body portion and the neck; said terminal portion being provided with a thread-receiving notch, and said terminal portion being likewise provided with a straight edge and with an upwardly-inclined rounded opposite edge through which said notch is produced. 85

11. A device of the character disclosed, 90 comprising a body portion provided with a tapering working end portion angularly related to the body portion and having a thread-receiving notch; said terminal portion rising above the upper end of the body 95 portion.

12. A device of the character disclosed, comprising a body portion provided with a tapering working end portion angularly related to the body portion and having a 100 thread-receiving notch; said terminal portion being disposed forwardly of the body portion and directed laterally of the plane thereof whereby said notch is disposed at one side of the plane of the body portion; 105 said body portion being provided with an angularly directed neck portion connecting the terminal portion with the body portion; the terminal portion having a rounded edge through which the notch is produced; said terminal portion rising above the upper end of the body portion.

In testimony whereof, I have signed my name to this specification in the presence of two subscribing witnesses.

HOWARD I. MORRIS.
